UNITED STATES PATENT OFFICE.

AXEL PERSON, OF ATTLEBORO, MASSACHUSETTS, ASSIGNOR, BY MESNE ASSIGNMENTS, TO WILLIAM DEMUTH & COMPANY, OF NEW YORK, N. Y., A CORPORATION OF NEW YORK.

CHECK PROTECTOR.

Application filed March 26, 1927. Serial No. 178,551.

This invention relates to check protectors. One of the objects thereof is to provide a check protecting device which is simple and convenient to use. Another object is to provide a device of the above nature which is thoroughly practical and efficient in operation. Another object is to provide a device of the above nature which is small and compact. Other objects are to provide a device of the above nature which is strong and serviceable and which is inexpensive. Other objects will be in part obvious or in part pointed out hereinafter.

The invention accordingly consists in the features of construction, combinations of elements, and arrangements of parts as will be exemplified in the structure to be herein-after described and the scope of the application of which will be indicated in the following claims.

In the accompanying drawing in which is shown one of the various possible embodiments of this invention,

Figure 1 is a plan view showing the device in operation;

Figure 2 is a sectional view taken as indicated by the line 2—2 of Figure 1;

Figure 3 is a side elevation, and

Figure 4 shows in greatly enlarged detail a small portion of one of the parts.

Similar reference characters refer to similar parts throughout the several views of the drawing.

Referring now to the drawing in detail, there is shown what may be termed a frame consisting of two arms 10 and 11 which extend in the same general direction and are spaced from one another. These two arms are preferably formed of one continuous member of sheet metal which is bent upon itself to the contour shown. In the arm 10 adjacent the free end thereof is mounted a roller 12 having a roughened or irregular surface, and in the arm 11 is mounted a similar roller 13. These rollers are positioned in the respective arms 10 and 11 with their axes substantially parallel and extending longitudinally of the arms. As is seen in Figure 2, the roller 12 is provided with a pair of trunnions 14 and 15 by which it is rotatably supported in an end flange 16 and an inner flange 17. These flanges 16 and 17 extend transversely of the arm 10 and are preferably formed integrally therewith,

the flange 16 being formed by a bent up end 55 portion of the arm 10 and the flange 17 being formed by striking up a portion of the metal, leaving an opening 17^a. The roller 13 is provided with trunnions 18 and 19 by which it is rotatably supported in flanges 20 60 and 21 similar to the flanges 16 and 17 respectively.

In addition to the transverse flanges 16 and 17, the arm 10 has a pair of longitudinally extending side flanges 22 and 23 extending alongside the roller 12 and substantially covering the sides thereof. The arm 11 has a pair of similar longitudinally extending side flanges 24 and 25.

The flanges 16, 17, 22 and 23 and the flanges 70 20, 21, 24 and 25 thus form, in effect, on the two arms 10 and 11, a pair of oppositely disposed substantially cup-shaped recesses in which the rollers 12 and 13 are respectively positioned. As may be seen from the 75 drawing, the rollers project very slightly above the edges of their surrounding flanges. The two rollers are thus substantially enclosed, the only portions thereof which are exposed being small portions of their operative surfaces which are positioned opposite to each other.

In the use of this device, the check is placed between the rollers 12 and 13, as is indicated in Figures 1 and 2. The two arms 85 10 and 11 are then urged toward each other by a slight pressure of the hand thereon to grip the paper of the check between the roughened surfaces of the rollers. With the rollers thus urged toward each other the 90 check is drawn through between the rollers, the rollers being thereby rotated. As the check is thus drawn between the rollers the roughened surfaces of the rollers disfigure the paper and leave imprints there- 95 in which afford a very secure protection against subsequent alteration of the check. The check is drawn through between the rollers in a direction transverse to the length 100 of the frame arms 10 and 11. The distance 100 between the inner ends of the rollers and the closed end 10^a of the frame is, without undue size of the device as a whole, easily made such that any desired portion of an ordinary check may be reached by the rollers. Generally it is desirable to disfigure the paper at least at the portion of the check on 105 which appears the name of the payee and

the amount to be paid. Preferably, as shown in Figure 1, the rollers are of a sufficient length to cover both these spaces in an ordinary check so that the complete operation 5 may be performed by simply drawing the check through between the rollers once.

It will be seen that this device is extremely simple, small and compact, and at the same time it accomplishes the desired result in an 10 efficient manner. The device may easily be carried in the pocket and hence is always available whenever the owner desires to write 15 a check. The rollers are substantially enclosed so that the device is not objectionable 20 to carry and, moreover, this feature gives the construction a neat and finished appearance. The side flanges 22, 23, 24 and 25 in addition 25 to enclosing the rollers, stiffen and strengthen the portions of the frame upon which the rollers are mounted so that these portions do not bend when the rollers are urged together. These side flanges terminate adjacent to the inner ends of the rollers, and the remainder 30 of the arms 10 and 11 have the required springiness to permit the rollers to be moved toward and away from each other. The surfaces of the rollers 12 and 13 may be roughened in various ways to give the desired result of disfiguring the paper drawn therebetween. For example, the surfaces of the rollers 35 may be deeply knurled. Preferably, however, the roller surfaces are made somewhat as indicated in Figure 4 in which there is shown a small portion of the roller 12. The surface 40 of the roller is provided with a multitude of small spaced projections 12^a and the roller 13 is provided with similar spaced projections. When the two rollers are brought together 45 to operate upon a sheet of paper, the projections on one mesh between the projections on the other, and a multitude of indentations are made in the paper from each side as it is drawn therebetween. The projections are of such length and size that they do not tear 50 the paper but simply disfigure and roughen its surface so that the characters previously formed thereon cannot be altered without the changes being at once apparent.

As many possible embodiments may be 55 made of the above invention and as many changes might be made in the embodiment above set forth, it is to be understood that all matter hereinbefore set forth or shown in the accompanying drawing is to be interpreted as illustrative and not in a limiting sense.

I claim as my invention:

1. In a check protector, in combination, a frame comprising a pair of arms extending in the same general direction, spaced apart, and connected together at one end, the free end of each of said arms being shaped to provide a housing of substantially semi-circular cross-section whose axis extends substantially lengthwise of the arm, the two housings on said arm facing each other, and each arm being provided with a pair of transversely directed flanges spaced apart from each other in a direction lengthwise of the arm for substantially closing the ends of the housing; and a pair of rollers positioned respectively within said two housings, the rollers being journaled in the spaced end-closing flanges of their respective housings, said rollers having roughened surfaces exposed toward each other and adapted to receive therebetween a paper check and said arms being of spring metal to permit said housings to be urged toward each other and to permit said rollers to be urged together to grip said paper check therebetween.

2. In a check protector, in combination, a frame comprising a strip of sheet metal bent upon itself to form two arms extending in the same general direction and spaced apart, the free end portions of said arms being offset in a direction away from each other, said offset portions being bent to provide pairs of laterally spaced flanges extending in the direction of their respective arms, thereby to form substantially cup-shaped recesses facing toward each other, each offset portion being provided with a transversely extending end flange for closing the outer end of its respective recess and each arm being provided with a transversely extending flange adjacent the inner end of each recess; and a pair of rollers positioned respectively within said recesses and journaled in the transversely extending flanges thereof, said rollers having roughened surfaces and said arms being adapted to be urged toward each other to cause said roughened rollers to engage therebetween the paper of a check and said rollers being adapted to rotate as said check is drawn therebetween in a direction crosswise of said arms.

In testimony whereof, I have signed my name to this specification this 19th day of March, 1927.

AXEL PERSON.
